UNITED STATES PATENT OFFICE.

WILLIAM E. FRANK, OF ST. LOUIS, MISSOURI, ASSIGNOR TO FOSTER BROS. MFG. CO., OF ST. LOUIS, MISSOURI, A CORPORATION OF MISSOURI.

TRUNDR-BED.

1,133,848.

Specification of Letters Patent. Patented Mar. 30, 1915.

Application filed February 28, 1914. Serial No. 821,748.

To all whom it may concern:

Be it known that I, WILLIAM E. FRANK, a citizen of the United States, and resident of St. Louis, Missouri, have invented certain new and useful Improvements in Trundle-Beds, of which the following is a specification containing a full, clear, and exact description, reference being had to the accompanying drawings, forming a part hereof.

My invention relates to improvements in trundle beds, and the object of my invention is to construct a trundle bed comprising a caster-bearing spring mattress frame and a head and foot, the posts of which serve as means for elevating and lowering the mattress frame, as well as to hold the bed clothing in place when folded.

With the above purposes in view my invention consists in certain novel features of construction and arrangement of parts as will be hereinafter more fully described, pointed out in the claims and illustrated by the accompanying drawings, in which—

Figure 1 shows in elevation a trundle bed constructed according to my invention, certain parts being broken away; Fig. 2 is an elevation of the trundle bed showing the head and foot in dotted lines in a folded position; Fig. 3 is an end view of the bed head; Fig. 4 is an inside face view showing the pivotal connection between one of the posts and the mattress frame; and Fig. 5 is an enlarged sectional plan of the pivotal connection between the posts and the mattress frame.

Referring by numerals to the accompanying drawings: 6 designates the side rails of the mattress frame.

7 designates the end rails which are supported in planes above the side rails on the upright 8.

At intervals the side rails are connected by the cross pieces 9 which constitute supports for the conical springs 10. At the tops of the springs there is a frame 11 which constitutes a support for the felt mattress or pad and the bed clothing.

12 designates the head of the bed, 13 the posts of the head and 14 the legs of the head, the posts 13 having bends adjacent their tops to hold the head out of the plane of the posts for purposes hereinafter made clear, and the legs are joined to the posts by integral semicircular portions 15.

By preference the head, the two posts and the two legs together with the semicircular portions 15 are constructed of single pieces of material, such as a tube or a rod.

16 designates a filler supported by the posts 13 and the head 12, the body of which lies in the plane of the head.

17 designates plates which are rigidly secured at the terminals of the legs 14 and pivotally secured on a rivet or bolt 18 to the side rails 6 of the spring mattress frame.

Carried by each of the plates 17 is a stop 19 arranged for engagement with the side rails of the mattress frame in order to hold the legs 14 and posts 13 in true vertical positions.

20 designates the foot of the bed which is an integral part of the posts 21 and legs 22 formed identically like the element comprising the head 12, except for the height of the posts which are somewhat shorter than the height of the posts of the head of the bed. And, like the legs 14, the legs 22 have connected at their extremities plates 23 constructed like the plates 17 and pivotally connected with the side rails of the bed frame on the pivots 24. The said plate 23 carries a stop 25. While the plates 23 are constructed like the plates 17 their positions are reversed relative to the plates 17.

26 designates a filler carried by the foot 20 and the posts 21 and is constructed on the same general lines as the filler 16 connected with the head of the bed.

27 designates hooks carried by each of the fillers 16 and 26 and arranged to engage with the end rails 7 of the bed, in order to lock the head and foot in raised position, as for use.

28 designates casters secured to the side rails 6 of the bed frame which constitute supports for the bed when in a knock-down position, as clearly shown in Fig. 2, wherein the ground line is elevated.

It is to be particularly observed that the pivot points 18 and 24 are spaced from the ends of the bed frame so that when the bed is completely folded the legs and said rounded portions thereof will lie within the length of the spring mattress frame, as clearly shown by dotted lines in Fig. 2. By reason of the bends 29 in the posts of the head and foot, the head and foot with their fillers 16 and 26 will lie in planes considerably above the spring mattress frame in 110

order to accommodate the felt mattress and bed clothing when the bed is folded.

When the bed is not in use it is generally in the folded position just described, so that it may be placed under an ordinary bed, the casters 28 providing means whereby the trundle bed may be readily moved.

The curved portions 15 of the bed supports form fulcrums of an arc shape which permit of an easy rocking of the bed frame in raising or lowering it.

I claim:

1. In a trundle bed, a frame, a bed leg pivotally connected with the frame, a bed post arranged in parallelism with and spaced part from the bed leg and an arc shaped connection between said leg and post.

2. In a trundle bed, a frame, a single rigid element, comprising a pair of legs, a pair of posts, a connection between the posts, and connections between the legs and posts, and means for pivotally connecting the legs to the frame, said posts being bent at their up-

per ends in order to hold the connection therebetween out of the plane of the posts, 25 for the purposes stated.

3. In a trundle bed, a frame, rollers carried by the frame, a pair of elements, constituting a bed head and a bed foot, each comprised in a single structure composed of 30 a pair of legs pivotally connected with the frame, a pair of posts forming part of the head and foot, arc shaped connections between the legs and posts, and connections between the posts, forming the bodies of the 35 head and foot, and means for securing the head and foot against movement relative to the frame when the bed is extended for use.

In testimony whereof I have signed my name to this specification in presence of two 40 subscribing witnesses.

WILLIAM E. FRANK.
